UNITED STATES PATENT OFFICE

MIHÁLY TABIS, OF MONTREAL, QUEBEC, CANADA

WATER MOTOR

Application filed April 25, 1929. Serial No. 358,036.

This invention relates to certain new and useful improvements in water motors of the type to be placed in the path of flow of a stream of water or waterfall with the water 5 rotating turbine wheels with power taken from the shafts thereof and has for its primary object to provide novel devices for controlling the operation of the water wheels and for holding them stationary while a 10 stream of water flows thereover when it is desired to place the motor out of use.

With the above and other objects in view that will become apparent as the nature of the invention is better understood, the same 15 consists in the novel form, combination and arrangement of parts hereinafter more fully described, shown in the accompanying drawings and claimed.

In the drawings:—

20 Figure 1 fragmentarily illustrates a concrete base or support for a water motor that is shown in side elevation and partly broken away;

Figure 2 is a vertical longitudinal sectional view through the water motor and concrete supporting base showing the water operated wheels of the motor and the brake shoes for arresting movement thereof;

Figure 3 is a horizontal sectional view 25 taken on line 3—3 of Figure 1 showing the exteriorly positioned operating mechanism for the water wheel brake shoes;

Figure 4 is a detail sectional view taken on line 4—4 of Figure 2 showing the interior 30 worm gear mechanism for raising the brake shoes; and

Figure 5 is a detail sectional view taken on line 5—5 of Figure 4 showing the vertically shiftable screw attached to the brake shoes 35 and operated by the worm gear mechanism.

The water motor is adapted to be positioned for intercepting the flow of a stream of water, such as a river or waterfall and is mounted upon and partially embedded in a 40 concrete base or foundation 1, the motor comprising a casing structure including a horizontal plate 2 anchored to the upper end of the hollow foundation 1 by bolts 3 set into the concrete and carrying a side platform 4 projecting laterally of the concrete foundation

as shown in Figure 2 and braced at its outer end by the inclined brace bars 5. The motor casing further includes a rectangular wall 6 depending from the plate 2 and set into the hollow foundation 1 with the lower end thereof flanged outwardly and extending into a pocket 7 formed in the inner face of the hollow foundation, the wall 6 being juxtaposed to the wall of the foundation as shown in Figure 2. The casing section 8 extending above the plate 2 is reversely curved inwardly, and then outwardly as at 8^a on the arc of a circle and is provided with an edge flange 9, the end walls of the upper casing section being curved while the side walls 10 extend vertically and are parallel with each other as shown in Figure 3. A top section, as shown in Figures 1 and 2, comprises straight side walls and curved end walls 11 flanged at their lower ends as at 12 to engage the flanges 9 to be bolted thereto as at 13, the curved walls 8^a and 11 cooperating to form end chambers 14 on the arc of a circle as illustrated. The upper ends of the curved walls 11 are directed inwardly and terminate at points spaced from each other with upwardly curved walls 15 forming end walls of a receptacle 16 at the upper end of the motor casing to receive water from a stream or falls. The motor casing in alignment with the wall 6 is provided with an interior casting comprising end walls 17 extending transversely of the casing and joined with the side walls 6 to form water passages 18, the lower ends of the walls 17 being flanged inwardly as illustrated in Figure 2. The upper ends of the walls 17 are connected by the head plate 19 extending transversely of the casing walls 6 as shown in Figures 2 and 4.

The outlet for the water motor includes a pipe 20 forked at its upper end as at 21 defining passages communicating with the passages 18, an inner wall 22 flanged to meet the lower flanged end of the wall 17 and to be bolted thereto as at 23, and an outer wall 24 outwardly flanged at its upper end to meet with the flange upon the lower end of the wall 6 and bolted thereto as at 25. A filling of concrete is indicated at 26 and extends from the foundation 1 through the walls 17

and 22 for further anchoring and supporting the motor casing. Water entering the chamber 15 is directed by the curved bottom wall 15 thereof through the motor casing and is separated by devices presently to be described and discharged through the side passages 18, 21 and outlet 20.

A pair of water wheels comprising end disk walls 27 and radially curved connecting blades 28 has its hub 29 fixed to the shaft 30 mounted in the side walls of the casing above the mounting plate 2, each water wheel being mounted concentrically within the curved end casing walls 8^a and 11, the spaced meeting edges of the two water wheels being disposed centrally of the bottom outlet 31 in the hopper 16 as shown in Figure 2.

The water wheel shafts 30 extend outwardly through one side wall 10 of the motor casing and into a compartment formed by the wall 32 shown in Figure 3 and of a shape in side elevation as illustrated in Figure 1 defining substantially circular communicating chambers 33. A gear wheel 34' is fixed to the projecting end of each shaft 30 within the chambers 33 and mesh with each other as shown in Figure 1, the meshing gear wheels 34' upon the shafts 30 insure steady and even rotation of the water wheels 27 and power is taken off the shafts 30 for any purpose desired, such as for the purpose of operating generators.

A pair of brake shoes is associated with the two water wheels for arresting movement thereof when it is desired to place the motor out of use, together with means for moving the brake shoes from operative to inoperative position. The brake shoes 34 are in the form of curved plates, shown more clearly in Figure 2, normally concentric with and spaced from the peripheral edges of the water wheels, the brake shoes being hingedly connected together at their upper ends as at 35, with the ends of the rod forming the hinged connection extending into vertical slots 36 formed in the side walls 10 of the motor casing. The lower end of each brake shoe 34 carries an end projecting rod extending into angle slots 37 in the walls 10 so that when the brake shoes are elevated, their upper hinged ends move upwardly between the water wheels while the lower ends of the brake shoes move upwardly and in a direction toward the peripheral edges of the water wheels with the brake shoes moving into engagement therewith for arresting movement thereof.

The devices for operating the brake shoes include a pair of screw rods 38, centrally disposed beneath the upper hinged edges of the shoes, one at each end thereof and having a link connection 39 with the shoes, the lower end of the screw depending into a cylinder or pocket 40 depending from the top wall 19 of the inner casting wall 17 as shown in

Figures 2 and 5. A worm gear 41 is threaded on the upper end of each screw 38 and is maintained against longitudinal movement on the screw by the bracket forks 42 engaged with the collar 43 depending from the worm gear 41. The shaft 44 has a pair of worms 45 fixed thereto, each worm engaged with one of the gears 41 while the shaft 44 extends at one end through the side wall of the motor casing as shown in Figures 1 and 4. A bevel gear 46 upon the extended end of the shaft 44 meshes with a bevel gear 47 upon the shaft 48 journaled in brackets 49 upon the plate 2 and platform 4. The other end of the shaft 48 carries a bevel gear 50 meshing with the bevel gear 51 upon the lower end of the vertical shaft 52 journaled in the standard 53 and having a hand wheel 54 upon its upper end. When it is desired to arrest rotation of the water wheels, the chain of shafts and gears is operated by the hand wheel 54 exteriorly of the motor casing for raising the brake shoes 34 that are guided by their rod extensions in the slots 36 and 37, the shoes moving upwardly into engagement with the edges of the water wheels for arresting movement thereof. Water will then flow into the hopper 16 from a river or falls and around the outer edges of the water wheels through the spaces 14 and discharged through the passages 18 and 21 to the outlet 20. When the brake shoes are lowered by the shaft and meshing gear arrangement described, the water from the hopper 21 flows downwardly through the central opening 31 to engage the curved blades 28 of the water wheels to rotate them and the shafts 30 from which power for suitable purposes may be taken.

From the above detailed description, it is believed that the construction and operation of the invention will at once be understood, and while there is herein shown and described the preferred embodiment of the present invention, it is nevertheless to be understood that minor changes may be made therein without departing from the spirit and scope of the invention as claimed.

I claim:

1. A water motor comprising a casing, a pair of water wheels rotatable therein in the same plane with adjacent peripheral edges spaced from each other, means in the casing operable exteriorly thereof adapted to be moved into engagement with the wheels for arresting movement thereof, a concrete support for the motor casing, said arresting means dividing the water flowing through the casing, and an outlet pipe having a fork at one end receiving the divided stream of water.

2. A water motor comprising a casing, a pair of water wheels rotatable therein in the same plane with adjacent peripheral edges spaced from each other, means in the casing operable exteriorly thereof adapted to be

5 moved into engagement with the wheels for arresting movement thereof, a concrete support for the motor casing, said arresting means dividing the water flowing through the
 10 casing, an outlet pipe having a fork at one end receiving the divided stream of water, said arresting means including a pair of hingedly connected arcuate brake shoe plates, and gear mechanism for raising and lowering the plates into and out of operative position.

15 3. A water motor comprising a casing, a pair of water wheels rotatable therein in the same plane with adjacent peripheral edges spaced from each other, means in the casing operable exteriorly thereof adapted to be moved into engagement with the wheels for arresting movement thereof, a concrete support for the motor casing, said arresting
 20 means dividing the water flowing through the casing, an outlet pipe having a fork at one end receiving the divided stream of water, said arresting means including a pair of hingedly connected arcuate brake shoe plates, gear mechanism for raising and lowering the plates into and out of operative position, guide rods on the hinged and outer edges of the plates, and guide slots in the adjacent casing walls for the rods to direct the brake shoe plates toward and away from the water
 25 wheels.

30 4. A water motor comprising a casing, a pair of water wheels rotatable therein in the same plane with adjacent peripheral edges spaced from each other, means in the casing operable exteriorly thereof adapted to be moved into engagement with the wheels for arresting movement thereof, a concrete support for the motor casing, said arresting
 35 means dividing the water flowing through the casing, an outlet pipe having a fork at one end receiving the divided stream of water, said arresting means including a pair of hingedly connected arcuate brake shoe plates, gear mechanism for raising and lowering the plates into and out of operative position, guide rods on the hinged and outer edges of the plates, and guide slots in the adjacent casing walls for the rods to direct the brake shoe
 40 plates toward and away from the water wheels, the gear mechanism including a pair of worm gear operated shafts attached at their upper ends to the hinged edges of the plates, and means exteriorly of the casing
 45 for operating the worm gears.

50 5. A water motor comprising a casing, a pair of water wheels rotatable therein in the same plane with adjacent peripheral edges spaced from each other, means in the casing operable exteriorly thereof adapted to be moved into engagement with the wheels for arresting movement thereof, a concrete support for the motor casing, said arresting
 55 means dividing the water flowing through the casing, an outlet pipe having a fork at one

end receiving the divided stream of water, said arresting means including a pair of hingedly connected arcuate brake shoe plates, gear mechanism for raising and lowering the plates into and out of operative position, 70 guide rods on the hinged and outer edges of the plates, guide slots in the adjacent casing walls for the rods to direct the brake shoe plates toward and away from the water wheels, the gear mechanism including a pair of worm gear operated shafts attached at their upper ends to the hinged edges of the plates, means exteriorly of the casing for operating the worm gears, and a gear wheel on each water wheel shaft in meshing engagement with each other.

75 In testimony whereof I affix my signature.
